552 Invention:
Lester Wolfe

By
Geo N. Goddard, Secy.

UNITED STATES PATENT OFFICE.

LESTER WOLFE, OF NEW YORK, N. Y.

FLYING TOP.

Application filed July 11, 1921. Serial No. 483,691.

To all whom it may concern:

Be it known that I, LESTER WOLFE, a citizen of the United States, and resident of New York city, in the county and State of New York, have invented certain new and useful Improvements in Flying Tops, of which the following is a specification.

This invention relates to flying tops and is intended to provide a toy of this kind which shall be capable both of flying in the air on the helicopter principle while also spinning upon the floor when the speed of rotation has diminished sufficiently to allow the flier to drop to the floor.

15 The invention comprises, generally speaking, a flying top having a generally circular structure with inclined or oblique wings and a central supporting or hub structure yieldingly supported upon an axial pin which 20 projects some distance both above and below the plane of the flier for the purpose of permitting it to spin on either end, so that when the flier rises to the ceiling in its flight the upper point of the pin will impinge against 25 the ceiling thus allowing the top to continue spinning and to descend and spin upon the floor when the force of gravity is greater than the lifting power of its vanes as the speed slackens.

30 This and other features of the invention will be particularly explained in the following specification and will be defined in the claims hereto annexed.

In the accompanying drawings I have 35 shown in detail one of the forms embodying the principles of this invention, in which:

Figure 1 is a vertical central section through the flying top when connected with its interwinding or torque device from 40 which its rotative impulse is received.

Figure 2 is a plan view illustrating the flier member proper with its clutch member secured thereto.

Figure 3 is a similar view with the clutching member removed.

Figure 4 is a side elevation in central section of the part shown in Figure 3.

Figures 5 and 6 show plan and vertical sectional views of the two members forming 50 the clutch portion adapted to the hub of the flier.

Figure 7 is an elevation of the winding or torque member.

Figures 8 and 9 are opposite end views 55 thereof.

Figure 10 is a detail showing both plan and sectional views of the torque spring and its anchoring member.

Figure 11 shows plan and central sectional views of the winding member by which the 60 free end of the torque spring is wound up.

Figure 12 shows plan and sectional views of the spring guiding member at the opposite end of the torque device or winding box.

Figure 13 is a detail view of the main 65 body or cylindrical member of the torque or winding box.

Figure 14 is a side elevation showing an 70 assembled view of the complete top as it appears when flying or spinning.

In the practice of this invention according to the form illustrated in the drawings, I form preferably out of a single disk of very light sheet metal a top comprising a domed hub or central member 1, a circular 75 rim or peripheral guard portion 2 and a series of oblique vanes 4 formed by cutting out radial T-shaped slots 3 in the intermediate portion of the disk at regular intervals and then bending to a suitable inclination 80 the intermediate wing portions 4 so that as the flier is rotated, let us say in a counter-clockwise direction, the vanes act to cause the air to lift the flier until the speed diminishes to the point where the gravity of the device 85 overcomes the lifting action. Immediately surrounding the domed part of the hub or central supporting structure are a series of arcuate slots 5. The coupling means by which the flier is detachably coupled with 90 its winding box or torque device comprises a disk or plate 10 provided with a vertical annular flange 11 which forms a guide for temporarily coupling together the winding box and the top which plate around its edge 95 inside of the flange 11 is provided with a series of arcuate slots corresponding to or registering with the slots 5 in the main flier member. The coupling member proper comprises the plate or disk 13 provided with an 100 annular peripheral flange terminating in short ears or lugs 14 arranged to register with the arcuate slots 5 and 12.

In assembling the flier the clutch member 13 is inserted inside the flange 11 of the 105 disk 10 with its ears projecting through the slots 12 as indicated in dotted lines in Figures 5, and this two part structure is then applied to the central spider or hub portion of the main flier member so that the ears 110

14 will pass through the slots 5 and be clinched on the underside of the flier hub by being turned outwardly as shown in Figure 1. The plate 13 of the clutch member 5 is provided with peripheral arcuate slots 15, adapted to receive a projecting tooth 24 of the winding member, presently to be described, and also has arcuate slots 16 at a slight distance from the central pin-receiving 10 perforation of the plate to be engaged by the hook 37 of the winding device.

It will be seen that the central openings of the plate 10 of the clutch member 13 and of the domed portion of the hub 1 are all 15 vertically aligned to receive an axial pin 17. Said pin is provided with a flanged collar 18 secured firmly thereto so as to receive the thrust of helical springs 19 and 20 disposed on opposite sides thereof and forming a 20 spring cushion against the longitudinal or axial movement of the pin in the bearing holes formed in the parts of the central supporting structure of the flier.

Obviously, the flier could not be conveniently operated without some means for imparting the necessarily rapid rotation, therefore about its axis to cause it to fly and spin. I have, therefore, provided an improved 25 starter or torque device which is constructed 30 to cooperate with the flier construction already described so as to impart thereto the necessary rotation or spinning movement.

The detailed construction of the various 35 parts of the form of the starting or winding device is illustrated in Figures 7 to 13 of the drawings, while Figure 1 shows the starting device operatively attached to the top or flier preparatory to setting the latter in rotation. An important feature of the 40 construction of this part of the invention resides in the structural details by which the starting device may be assembled out of individual parts capable of being formed of stamped metal without the use of solder, 45 screws or other fastening accessories.

The main winding device comprises a barrel or cylindrical member 22 formed by bending up a flat strip of metal into cylindrical form, the metallic blank being formed 50 on one end with a series of projecting ears 23 used for fastening the device together and with a projecting tongue 24 which serves as a stop member or tooth for locking the parts temporarily against rotative rotation in one direction, while leaving the member 55 free to turn in the contrary direction while winding up the spring.

It will be understood that Figure 1 shows the parts arranged so as to allow the flier 60 to be pushed off from its spring holder or starting device in order to fly upward, but it is clear that the device might be turned 65 up side down in which case the flier would fly downward toward the floor and spin on its then lowermost point without flying

above the level whence it started. The showing of the individual parts in elevation on Sheet 2 of the drawings, however, shows those parts disposed in just the reverse position to that shown in Figure 1. For convenience the end of the winding device carrying the interlocked tooth 24 may be called the coupling end of the device, while the end carrying the hand winding disk 36 at the anchored end of the torque spring may be called the winding end of the barrel. The active winding element is the coiled helical spring 35 whose anchored end is bent back on the coil of the spring as shown at 70 36^a to be inserted in an orifice 32 of the anchoring plate 30. The plate 30 is provided with outwardly flanged wings 31 to fit in between the projecting ears 33 formed on the winding end of the starter device and its interior edge is flanged in an axial direction to form a short annular guide against the exterior of the helical spring. A winding disk 35^a is formed out of a properly struck-up metallic disk and is provided with a peripheral rim 36 of sufficient width axially 75 to be conveniently grasped by the fingers and a central neck 37 which passes inside the helical spring to prevent it from gripping upon the central or axial spindle 17 when the spring is being wound up. As shown in Figure 11, the winding disk is provided with arcuate slots 38 formed to register with the ears 33 on the adjacent end of the barrel or cylinder 22 so that the ears may be bent inwardly after these parts are assembled together as shown in Figure 1 to secure them 80 together.

In the opposite or coupling end of the winding device is placed a guide plate 25 (see Figure 12) which has at its periphery an annular flange 26, and immediately adjacent to said flange a series of arcuate slots 28 adapted to register with the ears 23 of the barrel and the interlocking tongue 24 which also forms an extension of that end 90 of the barrel. This guide member also has an internal annular flange 27 to act as a guide to the free or coupling end of the spring. It is assembled by pushing it over the coupling end of the barrel with the 95 slots aligned to receive the ears 23 and the tongue 24. The ears are then turned inwardly to lock the guide in place, while the tongue 24 is allowed to project in an axial direction beyond the surface of the annular plate 25. The adjacent loose end of the 100 spring is formed with a hook as shown at 37 and also projects beyond the end of the barrel or guide member 25.

This hook 37 is extended to pass into any one of the three slots 16 formed in the coupling plate of the flier, while the projecting tooth 24 which is inclined on one side and has an abrupt shoulder or stop on the other side will pass through one of the peripheral 105 110 115 120 125 130

slots 15 of the coupling plate of the flier. Obviously, when the hub of the top is pressed over the coupling end of the barrel from which project the hook 37 and the tooth 24, the two devices will be operatively coupled together with the spring hooked into the coupling plate or member 13 and the tooth free to ride in one direction as the coupling member is rotated relatively to the top in order to wind up the spring. Of course, such rotative movement involves an axial lift or partial separation of the two members as the coupling plate 13 rides up the inclined surface of the tooth 24, but as soon as the portion of the plate between two adjacent arcuate slots 15 has passed over the top of the tooth endwise pressure of the flier toward the winding member brings the tooth into the next coupling slot and thus prevents the unwinding of the spring, while a new grip is taken by the hand to further turn or wind the spring. When the spring has been sufficiently wound for the purpose, the devices are held together in interlocked relation. It will be noticed that one end of the flier spindle 17 projects through the whole winding device so that when the finger or thumb is pressed against this projecting end the flier will be pushed off from engagement with the stop tooth 24 and under the torque of the wound-up spring is given a sudden rotative impulse which causes the flier to rotate with sufficient rapidity to fly upward. The upwardly projecting end of the spindle prevents the flier blades from striking against the ceiling which would otherwise result in stopping the rotation of the flier. This feature as well as the feature of mounting the spindle in the flier under a spring tension which keeps the parts snugly but yieldingly engaged has the beneficial effect not only of maintaining the spindle in proper operative axial relation to the flier at all times, but also allows the spindle to act as a shock absorber so that the sudden strong impact of the ends of the spindle either against the floor or against the ceiling does not tend to interfere with the spinning or to knock the assembled parts apart. The thrust spring also causes the flier to rebound when the peg or pin strikes upon the ceiling or floor.

What I claim is:

1. A flying top comprising a circular flier with oblique vanes, and a central hub portion provided with axial aligned openings, an axial pin projecting through said openings and held in yielding engagement with the hub portion by tensioning means acting in opposition to axial movement of the pin in either direction, substantially as described.
2. A flying top embracing in its construction, a central axial pin, a circular flier supported thereon by yielding tension springs

acting in an axial direction in opposition, said flier being provided with coupling means by which it may be detachably coupled with a spring winding device, substantially as described.

70

3. A flying top embracing in its construction an axial pin, a flier comprising oblique wings and a central connecting structure comprising upper and lower members held in spring pressed engagement in an axial direction against the axial pin, substantially as described.

75

4. A flying top embracing in its construction a circular flier comprising a series of oblique wings and a central supporting structure, an axial pin passing through and engaged with the central structure, the ends of said pin being both above and below the central structure to allow the top to spin upon either end, and means for yieldingly cushioning the pin against impact in both directions, substantially as described.

80

5. In a flying top the combination with a flier member provided with axially aligned openings, a spindle member passed through said openings and thrust springs engaged respectively with the flier and the spindle to exert a yielding pressure in opposite directions against the spindle, substantially as described.

90

6. The combination of a flying top embracing an axial spindle, and a circular flier having a central supporting structure operatively connected with the spindle so as to leave spinning ends both above and below the main plane of the flier, a slotted coupling member secured to the central structure, a starting device including a spring-containing casing, one end of the spring and one end of the casing projecting beyond the end of the casing to form respectively interlocking engagement with said coupling member, whereby rotation may be imparted to the flier when the coupling member is disengaged from said casing, substantially as described.

100

7. A flying top embracing in combination sheet metal main body member comprising an integrally formed central hub, outwardly projecting oblique vanes and a peripheral rim the hub being centrally perforated to receive an axial spindle, a thrust member arranged in opposition to said hub and adapted to engage the spindle, a central spindle projecting through both sides of the flyer top and having a peripheral projection intermediate of the hub member and the thrust member, and yielding springs interposed between said peripheral projection and said members to yieldingly resist shock in either direction against the pin, substantially as described.

105

1. A flying top comprising a circular flier with oblique vanes, and a central hub portion provided with axial aligned openings, an axial pin projecting through said openings and held in yielding engagement with the hub portion by tensioning means acting in opposition to axial movement of the pin in either direction, substantially as described.

110

2. A flying top embracing in its construction a central axial pin, a circular flier supported thereon by yielding tension springs

115

120

125

130

oblique wings all formed of a single piece of sheet metal, a slotted coupling member adapted to be engaged by a starting device, and an axially yielding spring mounted 5 spindle inserted in the hub at right angles to the main plane of the flier, substantially as described.

9. A starting device for a flying top comprising a split tubular casing held by and 10 interlocked with surrounding end heads, an anchoring plate supported at one end of said casing, a helical spring anchored to said plate and extending axially through

said casing and the other end head, and having at its free end a projecting hook for engaging the flying top, and an interlocking tooth projecting from the end of the casing adjacent to said free end of the spring to detachably interlock with the top to prevent unwinding of the spring when the starting device is operatively assembled with the flier, substantially as described. 15 20

In witness whereof, I have subscribed the above specification.

LESTER WOLFE.
